CANISTER

Melvin G. Miller, Houston, Tex.

Application July 5, 1949, Serial No. 3,703

Term of patent 14 years

(Cl. D58—17)

To all whom it may concern:

Be it known that I, Melvin G. Miller, a citizen of the United States residing at Houston, in the county of Harris in the State of Texas, have invented a new, original, and ornamental Design for a Canister, of which the following is a specification, reference being had to the accompanying drawings, forming a part thereof.

Figure 1 is a top plan view of a canister showing my new design;

Figure 2 is a side view thereof; and

Figure 3 is a side view taken at right angles to the view shown in Figure 2.

The dotted lines shown in the drawing are for illustrative purposes only.

I claim:

The ornamental design for a canister, as shown and described.

MELVIN G. MILLER.
